UNITED STATES PATENT OFFICE.

JOHN A. COMER AND LEE M. COMER, OF CALEXICO, CALIFORNIA.

CEMENT BUILDING FORM.

Application filed April 7, 1926. Serial No. 100,439.

This invention relates to apparatus for constructing cement buildings of all kinds and has for its object the provision of a novel form structure adapted to be set up at 5 the place where the building is to be erected so that when cement is poured in the walls and other elements will be formed.

An important object is the provision of a form structure in which the various parts 10 are readily adjustable so as to build walls and other elements of widely different sizes.

Another object is to provide a form structure for constructing posts or pillars as well as overhead beams, any or all of which may 15 be formed in conjunction with or separately from the wall structure.

An additional object is the provision of an arrangement of this character which will be comparatively simple and inexpensive to 20 manufacture, easy to set up and use, positive in action, efficient and durable in service, and a general improvement in the art.

With the above and other objects and advantages in view, the invention consists in 25 the details of construction and arrangement of parts to be hereinafter more fully described and claimed, and illustrated in the accompanying drawings in which:

Figure 1 is a perspective view of the form 30 set up ready for constructing a corner of a wall,

Figure 2 is a detail perspective view of a pair of the side plates,

Figure 3 is a perspective view of one of 35 the transverse supports,

Figure 4 is a perspective view of the closure structure for use at one end of a wall form,

Figure 5 is a perspective view showing an 40 arrangement for constructing a post or column,

Figure 6 is a perspective view showing the forms for making beams.

Figure 7 is a perspective view of a partition structure which may be used in forming 45 certain elements, and

Figure 8 is a perspective view showing an arrangement for forming a horizontal beam connected with a column or wall structure.

Referring more particularly to the drawings, we have shown the wall forming structure as including outer and inner form members designated generally by the numeral 10 and of similar construction, each including 50 plate members 11 and 12 arranged in overlapping relation and adjustably connected by

bolts 13 which pass through slots 14. The ends of the plate members 11 and 12 are provided with outstanding flanges 15 which may be bolted or riveted to the flanges of adjacent 60 plate members in the same plane as shown at 16 or in a plane at right angles thereto as shown at 17.

It is intended that the outer and inner form members be arranged in spaced relation and to maintain them at the proper distance apart, use is made of transverse braces 18 of angle bar construction notched or slotted at 19 for engagement upon the upper edges of the outer and inner plates or forms. 70 Use is also made of vertically-extending stays or posts 20 which may, in actual practice, be simply lengths of 2 x 4 scantling and it is preferable that the transverse brace members 18 be bolted or nailed thereto.

In case it is desired to provide a projection at one side of a wall, use may be made of angular plates 21 bolted or otherwise secured to the flanges at the ends of the plate members 12 and having their outer portions 80 over-lapping and slotted at 22 for the passage of clamping bolts 23 whereby the necessary or desirable adjustment may be maintained.

Whenever it is desired to close the end of 85 a wall form such as that above described, as for instance at a doorway or window opening, use is made of plates 24 bolted to the outstanding flanges at the ends of the plates 12 and arranged in overlapping relation, these plates 24 being formed with slots 25 for the passage of securing bolts 26 for maintaining an adjusted position.

In Figure 5 we have illustrated the form structure for constructing posts, pillars or 90 columns of rectangular form in cross section, and referring to this figure it will be seen that we have provided right angularly shaped plate members 28 arranged in vertical position and in overlapping relation, the 100 overlapping portions being slotted at 29 for the passage of securing bolts 30 for maintaining an adjusted position.

Whenever it is desired to provide a column structure at the end, for instance, of a wall 105 and to have the column structure formed integrally with the wall but spaced above the floor, use may be made of the slidably mounted overlapping partition plate members 31, shown in Figure 7, these plate members 110 having depending flanges 32 adapted to be secured to the opposite sides of a post

or column mold, or against the opposite sides of a wall mold, in case such is desired, as for instance when making window openings, these plates having slots 33 through which 5 pass clamping bolts 34 for adjusting purposes.

Whenever it is desired to form beams, use is made of the structure illustrated in Figure 6 in which we have disclosed two 10 interfitting and slidably engaged trough members 35 and 36 slotted at 37 for the accommodation of securing bolts 38.

For forming a beam as the continuation of the upper portion of a wall projection 15 such as is formed by the members 21, we make use of the beam molds just described or single trough members 39 disposed at the upper ends of the members 21 and held thereto as by angular brackets 40. Extension side plates 41 may also be provided in 20 connection with the upper ends of the sides of the members 21 and connected with the ends of the trough 39, all as illustrated in Figure 8.

From the foregoing it will be seen that 25 we have provided mold members capable of association to form practically any building construction. After the molds are all set up it is obvious that cement may be poured 30 in and permitted to set after which the molds are removed. As the mold members are constructed of metal it is evident that 35 they should be durable and capable of prolonged use without bending, buckling or becoming otherwise deranged.

While we have shown and described a 40 preferred embodiment of the invention, it should be understood that we reserve the right to make such changes in the form, construction and arrangement of parts as will not depart from the spirit of the invention or the scope of the subjoined claims.

Having thus described the invention, we 45 claim:

1. In a wall mold, outer and inner mold

members each formed as a pair of longitudinally slidably adjustably connected plates provided at their outer ends with right angularly extending flanges adapted for connection with adjacent mold members, upright supports located in spaced parallel relation outwardly and inwardly of the outer and inner mold members respectively, and means connected with said uprights and engaging the outer and inner members for 50 maintaining the latter in spaced relation, said means comprising brace bars of angular formation in cross section adapted to be bolted to the uprights and having slots receiving the upper edges of the plates of the 55 outer and inner mold members.

2. In a wall mold, outer and inner mold members each formed as a pair of longitudinally slidably adjustably connected plates provided at their outer ends with right angularly extending flanges adapted for connection with adjacent mold members, and other vertically extending angular plate members having outstanding flanges adapted 60 to be secured to the first named plates, said 65 angular plate members being laterally slidably adjustably connected.

3. In a wall mold, outer and inner mold members each formed as a pair of longitudinally slidably adjustably connected plates provided at their outer ends with right angularly extending flanges adapted 70 for connection with adjacent mold members, and other vertically extending angular plate members having outstanding flanges adapted 75 to be secured to the first named plates, said angular plate members being laterally slidably adjustably connected, in combination with a trough-like beam mold detachably connected with the upper ends of the 80 assembled angular plate members.

In testimony whereof we affix our signatures.

JOHN A. COMER.
LEE M. COMER.
